(57) **CLAIM**

The ornamental design for a portion of a display panel or screen with an icon, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a portion of a display panel or screen with an icon showing our new design.

The dot-dash broken line showing of the portion of the display panel or screen is included for the purpose of illustrating environmental structure and forms no part of the claimed design.
